Primary Examiner — Joseph Kukella*Assistant Examiner* — Darryl J Dardenne(74) *Attorney, Agent, or Firm* — Wolf, Greenfield & Sacks, P.C.(57) **CLAIM**

The ornamental design for a beverage machine, as shown and described.

DESCRIPTION

FIG. 1 is a top, front, left side perspective view of a beverage machine;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom view thereof; and,

FIG. 8 is top, front, right side perspective view thereof.

The short dash-long dash broken lines illustrate boundaries of the claimed design and form no part of the claimed design. The dash-dash broken lines illustrate portions of the beverage machine that form no part of the claimed design.

1 Claim, 8 Drawing Sheets
